UNITED STATES PATENT OFFICE.

WILLIAM B. WEEDEN, OF PROVIDENCE, RHODE ISLAND.

DESIGN FOR WOVEN FABRIC.

Specification forming part of Design No. 7,851, dated November 10, 1874; application filed September 5, 1874.
[Term of Patent 3½ years.]

CASE A.

To all whom it may concern:

Be it known that I, WILLIAM B. WEEDEN, of the city and county of Providence, in the State of Rhode Island, have invented a new Design for Fancy Cassimere Fabrics; and I do hereby declare that the following specification, taken in connection with the drawings making a part of the same, is a full, clear, and exact description thereof.

The design resides in the effect produced from the combination of the peculiarly composed stripes A, with alternate plain stripes B. The stripes A are composed of narrow stripes of so-called "crape-cord" weaving *a a*, alternating with narrow stripes of plain weaving *b b*, the said stripes A being crossed at regular intervals with the transverse bars *c*. The stripes B are woven plain, and alter-

nate with the stripes A, which latter are so arranged that the cross-bars *c*, of alternate stripes only, shall coincide with the same transverse line.

The fabric may be made in any preferred variety or combination of colors, for giving effect to the design above described, the characteristic feature of which is the corded and cross-barred stripes A, in combination with the plain stripes B.

What I claim as my invention is—

The design for cassimere fabrics as herein set forth, and represented in the drawings.

WILLIAM B. WEEDEN.
